UNITED STATES PATENT OFFICE.

AMOS H. HOLTZINGER, OF BEDFORD CITY, VIRGINIA.

CHIMNEY-COWL.

No. 867,881.

Specification of Letters Patent.

Patented Oct. 8, 1907.

Application filed May 23, 1907. Serial No. 375,347.

To all whom it may concern:

Be it known that I, AMOS H. HOLTZINGER, a citizen of the United States, residing at Bedford City, in the county of Bedford and State of Virginia, have invented 5 new and useful Improvements in Chimney-Cowls, of which the following is a specification.

This invention relates to improvements in chimney cowls, comprehending the provision of a simple and effective device of this character adapted to be securely 10 mounted in position upon the chimney and including a box formed of a base section and a hood carrying section, the latter being designed for ready removal and convenient reapplication, as occasion may require in 15 cleaning the chimney, making repairs and other similar operations.

The invention consists of the features of construction and combination of parts, hereinafter fully described and claimed, and is illustrated in the accompanying drawing, in which:—

20 Figure 1 is a perspective view illustrating the application of the cowl to a chimney. Fig. 2 is a side elevation of the cowl detached. Fig. 3 is a cross section thereof on the line of the spring catches. Fig. 4 is a side elevation of the base section.

25 Referring to the drawing, 1 represents a conventional form of brick chimney, and 2 the improved cowl applied thereto.

The cowl comprises a box or chambered body comprising a base section 3 and a hood-carrying section 4, 30 said box or body being preferably of oblong rectangular form to correspond substantially to the shape of the chimney flue. The base section 3 is preferably, like the hood-carrying section 4, formed of sheet metal and is provided at its lower end with an anchoring flange 35 or projection 5 extending around the same, and above said flange is formed with an external bead or shoulder 6.

Said section 3 occupies the upper portion of the flue opening in the chimney 1 with its bead or shoulder 6 resting upon the upper surface of the upper tier or 40 course of bricks 7 and closing the joint between the same and box, while the flange 5 underlies the course 7 and is arranged between the same and the course of bricks below, being thereby bound or held in position by the upper course. The bricks are cemented or 45 otherwise bound in the usual way, thereby firmly and permanently fastening the base section 3 in position to prevent any possibility of the cowl being displaced by wind pressure or otherwise rendered unserviceable in use. The cowl-carrying section 4 is adapted to slip 50 down or telescope over the upper portion of the section 3 and to rest against the upper surface of the bead or shoulder 6, and said section 4 is provided at opposite sides with spring latches 8 projecting inwardly through

openings therein and adapted to snap into corresponding keeper openings 9 in the section 3, thus securely 55 and detachably fastening the section 4 in position. The top of the section 4 has the upper edges of its side walls beveled and its end walls provided with concaved recesses to receive the tubular hood 10 which seats therein and is riveted or otherwise fastened thereto, 60 solder or other means being preferably employed to close the joints. The hood 10 extends longitudinally of the box and projects beyond the end of the same, its ends being beveled or inclined downwardly, as indicated at 11, to secure an effective draft. 65

It will be seen from the foregoing description that the base section of the device may be firmly and permanently fastened in position upon the chimney, while the top or hood-carrying section may be applied and removed at will, thus enabling it to be conveniently detached, when it is necessary to repair or clean 70 the chimney or when the substitution of a new hood-carrying section is necessary, and as readily and conveniently placed in position. That portion of the base of the hood which is confined within the boundary 75 of the box is provided with an opening 12 communicating with the box for the discharge of the products of combustion.

Having thus described the invention, what is claimed as new, is:—

1. A chimney cowl in the form of an oblong rectangular box comprising a base section, a cowl-carrying section telescopically engaging the base section, projections upon said base section to extend over and beneath the top course of bricks of a chimney, the upper projection forming a support and stop to limit the downward movement of the cowl-carrying section, fastening means for detachably connecting said sections, and an elongated tubular hood or cowl mounted upon said cowl-carrying section. 80

2. A chimney cowl in the form of an oblong rectangular box comprising a base section provided with a surrounding basal flange to extend beneath the top course of bricks of a chimney, and a shoulder above said flange to rest upon the upper surface of the bricks, and a hood or cowl-carrying section detachably mounted upon the upwardly projecting portion of said base section and resting upon and limited in downward movement by said flange. 85

3. A chimney cowl in the form of an oblong rectangular box comprising a base section having an external basal anchoring flange extending around the same, and an external shoulder arranged above said flange, a top section telescopically engaging said base section and adapted to rest upon the flange, means for detachably connecting said sections, and a cowl comprising a tube horizontally mounted upon the top section. 95

In testimony whereof, I affix my signature in presence of two witnesses.

AMOS H. HOLTZINGER.
